HARTLEY ELLIS, OF CLEVELAND, OHIO, ASSIGNOR OF TWENTY-ONE FORTIETHS TO
ELIZABETH M. ELLIS, OF ERIE, PENNSYLVANIA

CLOSURE FOR METALLIC DRUMS AND THE LIKE AND METHOD OF MAKING SAME

Application filed March 3, 1928. Serial No. 258,752.

The present invention, as indicated, relates to a closure for metallic drums, and the like, and method of making same, and the primary object thereof is to provide an inexpensive but efficient closure of the type indicated which may be easily attached to or removed from the drum and which will provide a practically air-tight closure. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

20 Fig. 1 is a plan view of a drum with a closure of the type contemplated by the present invention attached thereto; Fig. 2 is a fragmentary vertical section thereof; Fig. 3 is a fragmentary plan view of the drum header; Figs. 4, 5, and 6 are sectional views of details of construction.

Referring more particularly to the drawings, the reference numeral 1 indicates a drum, or the like, provided with an annular header indicated generally at 2, said header being secured to the drum by any well known type of joint such as is indicated at 3. The header 2 is bent to provide a substantially horizontal annular shelf 4 bounded at its outer edge by a vertical shoulder 5, and a second narrower shelf 6 is depressed below the level of the shelf 4 at the inner edge of the latter. A down turned flange 7 depends from the inner edge of the shelf 6. At spaced points about the surface of the shelf 4 upwardly projecting lugs 8 are provided. These lugs are preferably headed rivets suitably secured in the metal of the shelf 4.

40 The closure proper, indicated generally at 9, is a disk-like member formed with a central depressed portion 10 and an annular flange 11. The flange 11 is formed with a plurality of spaced keyhole slots 12 adapted to cooperate with the lugs 8. Each of the 50 slots 12 is bounded laterally by cam members

18. Each of said cam members comprises a gradually sloping face 14 extending from a point adjacent the large end of the keyhole slot to an apex 15, and a suddenly sloping face 16 extending from said apex to a point 55 adjacent the other end of the slot.

A resilient washer 17 which is annular in shape and circular in cross section under normal conditions is adapted to rest upon the shelf 6 of the header 2.

In use, after the drum has been filled, the closure 9 is placed in position on the header, attention being called to the fact that the depressed portion 10 fits snugly within the depending flange 7 of the header 2. The heads of the lugs 8 are of such size as to be insertable through the large ends 19 of the slots 12. When the closure has been brought into this position, it rests upon the washer 17. Rotation of the closure in a clockwise direction, as viewed in Fig. 1, will cause coaction of the cam faces 14 with the conical heads 18 of the lugs 8 to cause the washer 17 to be compressed. It will be seen that the shelf 6 and its shoulder cooperate with the closure 9 and its flange 11 to enclose the washer 17 to prevent extrusion thereof upon the exertion of such pressure. Consequently a very tight closure may be obtained in the above manner.

80 In the manufacture of the closure contemplated by the present invention, the flanged disk-like member is first formed by stamping or spinning, and thereafter the keyhole slots are formed. It is to be understood that these slots may be formed simultaneously or individually. Preferably, the flange is punched to form the circular apertures 19, after which a wedge-shaped piece, the base of which intersects the aperture 19 and the apex of which coincides with the point 15 is cut out, and a second wedge-shaped piece having an apex with less acute angularity and having its apex coincident with the apex of said first wedge-shaped piece is cut out. It will readily be seen that the above described cutting results in two meeting substantially triangular flaps which may be bent upwardly to form the cam members 13 and the slots 20 intersecting the apertures 19.

In closing the container, a compression of the washer or gasket is first obtained from a portion of the coned heads 18 of the lugs 8 and then additional pressure is obtained by the rise of the cam members 13. When the apex 15 of each cam member passes beyond its rivet head, the closure is forced by the resilience of the gasket 17 to move slightly upward, guided by the sloping faces 16 until the end of the slot strikes the rivet thus locking the closure in place, since to open, the closure must move downwardly a trifle to permit the apex 15 of each cam surface to pass its rivet head. The angle of the cam members 13 may also be varied slightly with respect to the plane of the closure head to obtain an increased compression and the entire range may be readily varied by varying the shape of the members. Preferably a U-shaped member 21 is attached to the upper surface of the closure by rivets 22 or the like, to receive a bar for use in rotating the closure member and the friction to be overcome is very considerable.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. The combination with a metallic drum, or the like, having an annular header, of a disk-like closure therefor comprising a central depressed portion adapted to fit within said header and an annular flange adapted to overlie said header, said flange being formed with a plurality of spaced keyhole slots and cam members at the lateral edges of said slots, the surface of each of said cam members rising from a point adjacent the enlarged end of said slot to a point just short of the other end of said slot, and dropping from said last-mentioned point to said other end of said slot said header being provided with a plurality of correspondingly spaced headed lugs for cooperation with said cam members.

2. The combination with a metallic drum, or the like, provided with an annular header, said header being bent to provide a substantially horizontal annular shelf shouldered at its outer edge, a second annular shelf depressed below the inner edge of said first shelf, and a down-turned annular flange at the inner edge of said second shelf, and a plurality of upwardly projecting headed lugs spaced around said first shelf, the head of each of said lugs being formed as an inverted cone, of a disk-like closure for said drum comprising a central depressed portion adapted to fit snugly within said down-turned flange and an annular flange adapted to over-

lie said first shelf and to abut the external shoulder thereof, an annular washer of circular cross section adapted to rest on said second shelf and adapted to be enclosed by said shelf and said closure, said flange being provided with a plurality of keyhole slots for cooperation with said lugs, and cam surfaces bounding said slots and adapted to cooperate with the lower surfaces of the heads of said lugs to cause rotation of said closure member to compress said washer.

3. The combination with a metallic drum, or the like, having an annular header, of a closure therefor comprising a disk-like member formed with a central depression adapted to fit within said header, the rim of said closure being formed with a plurality of keyhole slots bounded by cam surfaces, and a plurality of headed lugs on said header, said lugs being adapted to enter said slots, and the heads of said lugs being adapted to cooperate with said bounding cam surfaces.

4. The combination with a metallic drum, or the like, having an annular header, of a closure therefor comprising a disk-like member formed with a central depression adapted to fit within said header, the rim of said closure being formed with a plurality of keyhole slots bounded by cam surfaces, and a plurality of projecting lugs on said header, each of said lugs being formed, at its free end, with a substantially conical head, said lugs being adapted to enter said slots, and the conical surfaces of said heads being adapted to cooperate with said cam surfaces.

5. The combination with a metallic drum, or the like, having an annular header, of a closure therefor comprising a disk-like member formed with a central depression adapted to fit within said header, the rim of said closure being formed with a plurality of keyhole slots bounded by adjustable cam members, and a plurality of projecting lugs on said header, each of said lugs being formed, at its free end, with a substantially conical head, said lugs being adapted to enter said slots, and the conical surfaces of said heads being adapted to cooperate with said cam members.

6. In a closure for a metallic drum, or the like, having an annular header provided with an upstanding headed lug, a disk-like member having a keyhole slot adjacent its rim, cam surfaces bounding said slot, each of said cam surfaces rising from a point adjacent the enlarged end of said slot to a point just short of the other end of said slot, and dropping from said last-mentioned point to said other end of said slot, said lug being adapted to enter said slot, and said head being adapted to cooperate with said cam surfaces.

7. In a closure for a metallic drum, or the like, having an annular header provided with an upstanding headed lug, a disk-like member having a keyhole slot adjacent its rim,

cam surfaces bounding said slot, each of said cam surfaces rising gradually from a point adjacent the enlarged end of said slot to a point just short of the other end of said slot, and dropping suddenly from said last-mentioned point to said other end of said slot, said lug being adapted to enter said slot, and said head being adapted to cooperate with said cam surfaces.

- 10 8. In a closure for a metallic drum, or the like, having an annular header provided with an upstanding headed lug, the head of said lug being shaped as an inverted cone, a disk-like member having a keyhole slot adjacent 15 its rim, cam members bounding said slot, the surface of each of said cam members rising from a point adjacent the enlarged end of said slot to a point just short of the other end of said slot, and dropping from said last- 20 mentioned point to said other end of said slot, and each of said cam members being adjustable in a direction transverse to the length of said slot, said lug being adapted to enter said slot, and said head being adapted 25 to cooperate with said cam surfaces.

Signed by me this 1st day of March, 1928.
HARTLEY ELLIS.
